WARP BEAM TRANSFERRING APPARATUS

Clay L. Young, Sr., Red Springs, N. C.

Application February 15, 1943, Serial No. 475,992

2 Claims. (Cl. 214—65)

This invention relates to new and useful improvements in apparatus for handling full warp beams, the principal object of the invention being to provide apparatus for transferring full warp beams from warp beam trucks to looms.

An important object of the invention is to provide a transferring apparatus of the character stated whereby full and consequently heavy warp beams are transferred in an almost effortless manner from conveying trucks to the usual supporting bearings on looms.

Other important objects and advantages of the invention will become apparent to the reader of the following description.

In the drawings—

Figure 1 represents a side elevational view of the apparatus as employed in conjunction with a truck and loom.

Figure 2 is a sectional view taken substantially on the line 2—2 of Figure 1.

Figure 3 is a vertical sectional view through the truck showing the elevating means.

Figure 4 is a fragmentary side elevational view showing one of the truck posts with a guide plate thereon.

Figure 5 is perspective view of one of the lifters.

Figure 6 is a perspective view of the stand.

Figure 7 is a perspective view of a jack for lifting the truck.

Figure 8 is a perspective view of one of the tracks.

Figure 9 is a perspective view of one of the guide plates.

Referring to the drawings wherein like numerals designate like parts, it can be seen in Figure 1 that numeral 5 denotes the frame of a loom having the usual bearing structures 6 thereon formed with bearing seats 7, 8. The top of the frame 5 has notches 9 therein, especially in the Draper type of loom illustrated.

Numerical 10 generally refers to a conventional type of warp beam truck which includes side beams 11, 11 and end members 12, 12, joined together to make a rectangular-shaped frame preferably of angle iron members as represented in Figure 3.

Each end member 12 of the truck is supported by a wheel 13 and from each of these members 12 rises a pair of closely spaced angle iron posts 14, 15.

As can be seen in Figure 1, each post 14 has an inclined slot 16 therein for receiving the corresponding journal 17 of a warp beam 18. The posts 14, 15 are joined together by a bridge member 18a at their upper ends.

In carrying out the present invention, a guide plate 19 is secured to each post 15, it being preferable that the plates 19 each have a vertically disposed bolt receiving slot 20 at its upper end and a bayonet slot 21 at its lower end for the purpose of quickly engaging bolts 22, 23 on the posts 15. As can be seen in Figure 9, the guide plate 19 has a laterally disposed portion 24 formed with a vertically disposed guide slot 25 for receiving one end portion of a track 26. As can be seen in Figures 1 and 2, each track 26 has a plurality of closely spaced openings 27 at the end portion thereof which extend through the slot 25 of the corresponding plate 19, and a detent head 28 at its opposite end for embracing the corresponding notched portion 9 of the loom frame 5.

Each track 26 has a chain 29 anchored as at 30 to the apertured end of the same, the other end of the chain being provided with a pin 31 which can be disposed into any one of the openings 27 at the outside of the corresponding guide plate 19, in a manner clearly shown in Figure 1.

In order to lift the truck and thus provide a non-movable stand therefor, two devices are employed, namely, a stand generally referred to by numeral 32 (see Figure 3) and a jack 33.

The stand 32 may be composed of a base 34 and a riser 35 rising therefrom, the same having one wall 36 inclined to reduce the riser to a thin neck 36. The neck 36 is provided with a hook head 37 which is capable of being engaged over the upper flange of the corresponding end member 12, as in the manner shown in Figure 3.

The jack 33 is more or less conventional, the same comprising a base 38 from which rises a rack formed post 39 and on which is adjustable a carriage structure 40 having an operating arm 41 and a grooved shoe 42 which engages under the end member 12 at the opposite end of the truck frame.

Obviously, when the jack 33 is operated to lift the corresponding end of the truck, the wheel 13 at the opposite end of the truck will also be raised slightly off the ground so that the latter end of the truck is supported by the stand 32. The truck is also provided with a pair of intermediate wheels 18a.

A lifter unit generally referred to by numeral 43 is provided for each track 26. Each lifter 43 comprises a pair of angle members 44, 44, companion ends of which are secured by bolts 45 to one end of a handle 46. Interposed between the remaining portions of the angle members 44 are grooved rollers 47, 48, while depending from a

pin 49 bridging the heel portions of the angle members 44, 44 is a swingable hook structure 50.

It can now be seen, that the truck is first moved to a point adjacent the loom, with the journal 16 of the beam 18 properly aligned with the bearings 6. The truck is now jacked up by the use of the stand 32 and the jack structure 33. Thus the wheels 13, 13 are elevated from the floor and the truck is immovable.

The tracks 26, 26 are now placed in position, the detent 28 being properly positioned on the notched portions of the frame 5 with the apertured ends of the tracks disposed through the slots 27 of the guide plates 19. When the tracks have been properly positioned, the pins 31 are positioned in the proper openings 27.

Two men only are required for this positioning of the parts named, and only two men are required to operate the lifters 43. These lifters are positioned with the rollers 47, 48 on the tracks 26. The hooks 50 are engaged with the journals 17 of the full warp beam 18 and obviously by rocking the lifters so that the lifter will ride the rollers 47, the hooks 50 will lift the journals 17 from the slots 16. The full warp beam is now suspended by the lifters and the lifters can be allowed to ride slowly down the tracks 26 until the rollers 47 engage a cross beam 52 on the loom. The journals 17 will now be substantially resting 30 in the notches 7 of the bearing 6 and the warp beam can rest at this point until slack is taken out of the warp.

The next operation is to press down on the handles 46, causing the lifters to rock on to the rollers 48 and thus the journals 17 are lifted into 35 the bearing recesses 8 of the bearing 6. The

transferring apparatus can now be disassembled and moved to some out of the way point.

While the foregoing specification sets forth the invention in specific terms, it is to be understood that numerous changes in the shape, size and materials may be resorted to without departing from the spirit and scope of the invention as claimed hereinafter.

Having described the invention, what is claimed 10 as new is:

1. Transferring apparatus for warp beam transporting trucks comprising jack means for a warp beam truck, tracks adapted to bridge a truck with a loom and carriage means for disposition on the tracks for carrying a warp beam from the truck to the loom, said carriage means each comprising a pair of roller units adapted to ride the tracks and each roller unit including spaced rollers, a handle for rocking each unit, each unit being provided with a hook for engaging the corresponding journal of a warp beam, said hook being positioned between said spaced rollers to equalize the load on both rollers and to utilize either of said rollers as a pivot for the handle.

2. Transferring apparatus for warp beam transporting trucks comprising jack means for a warp beam truck, tracks adapted to bridge a truck with a loom and carriage means for disposition on the tracks for carrying a warp beam from the truck to the loom, said jack means comprising a fixed stand for supporting one end of the truck and an elevatable jack for engagement with the other end of the truck.

CLAY L. YOUNG, SR.
